Primary Examiner — Deanna L Pratt*Assistant Examiner* — Lilyana Bekic(74) *Attorney, Agent, or Firm* — Brinks Gilson & Lione(57) **CLAIM**

The ornamental design for an oscillating positive expiratory pressure device, as shown and described.

DESCRIPTION

FIG. 1 is a perspective view of an oscillating positive expiratory pressure device showing the new design;

FIG. 2 is a rear view thereof;

FIG. 3 is a front view thereof;

FIG. 4 is a top view thereof;

FIG. 5 is a bottom view thereof;

FIG. 6 is a left-side view thereof; and,

FIG. 7 is a right-side view thereof.

The broken lines in the drawings illustrate portions of the oscillating positive expiratory pressure device that form no part of the claimed design.
